WHEEL

Thomas L. Hibbard, Birmingham, Mich., assignor to Kelsey-Hayes Company, Romulus, Mich., a corporation of Delaware

Filed July 17, 1964, Ser. No. 80,907

Term of patent 14 years

(Cl. D14—30)

FIGURE 1 is an elevational view of a wheel showing my new design;

FIG. 2 is a diametrical cross sectional view thereof; FIG. 3 is a reduced scale perspective view thereof; and FIG. 4 is a cross sectional view of a spoke of the wheel taken along the line 4—4 of FIGURE 1.

I claim:

The ornamental design for a wheel, substantially as shown.
